US00D984731S

(12) **United States Design Patent** (10) Patent No.: **US D984,731 S**
(45) Date of Patent: **** Apr. 25, 2023**

(54) **ELECTRONIC CIGARETTE**

- (71) Applicant: **SHENZHEN ZUN YI PIN TECHNOLOGY CO., LTD.**, Shenzhen (CN)
- (72) Inventors: **Miaowen Yang**, Shenzhen (CN); **Yusen Dong**, Shenzhen (CN); **Shaoqing Yan**, Shenzhen (CN); **Yonghui Lin**, Shenzhen (CN); **Huifu Shuai**, Shenzhen (CN)

- (73) Assignee: **SHENZHEN ZUN YI PIN TECHNOLOGY CO., LTD.**, Shenzhen (CN)

(**) Term: **15 Years**

(21) Appl. No.: **29/805,889**

(22) Filed: **Aug. 31, 2021**

(51) LOC (14) Cl. **27-02**

(52) U.S. Cl.

USPC **D27/162**

(57) **CLAIM**

The ornamental design for an electronic cigarette, as shown and described.

DESCRIPTION

FIG. 1 is a front perspective view of an electronic cigarette of the present disclosure;

FIG. 2 is a top perspective view thereof;

FIG. 3 is a front elevational view thereof;

FIG. 4 is a rear elevational view thereof;

FIG. 5 is a left-side elevational view thereof;

FIG. 6 is a right-side elevational view of thereof;

FIG. 7 is a top plan view thereof; and,

FIG. 8 is a bottom plan view thereof.

The broken lines shown in the drawings represent portions of the electronic cigarette and form no part of the claimed design.
